UNITED STATES PATENT OFFICE

165,095

FOUR-IN-HAND NECKTIE

William L. Mitchell, Omaha, Nebr.

Application July 14, 1951, Serial No. 15,873

Term of patent 14 years

(Cl. D3—16)

To all whom it may concern:

Be it known that I, William L. Mitchell, a citizen of the United States, residing at Omaha, in the county of Douglas and State of Nebraska, have invented a new, original, and ornamental Design for a Four-in-Hand Necktie, of which the following is a specification, reference being had to the accompanying drawing, forming a part thereof.

Figure 1 is a perspective view of a four-in-hand necktie depicting certain portions of two sides and one edge thereof and showing my new design.

Figure 2 is a view similar to Figure 1 and showing an oppositely disposed edge with respect to the said edge shown in Figure 1, together with the opposite sides of the said certain portions shown in Figure 1.

The diagonally disposed lines of Figure 1 represent a green color.

I claim:

The ornamental design for a four-in-hand necktie, as shown and described.

WILLIAM L. MITCHELL.
